US00D625722S

(12) **United States Design Patent**
Park

(10) **Patent No.:** **US D625,722 S**
(45) **Date of Patent:** **** Oct. 19, 2010**

(54) **OPTICAL DISK DRIVE**

(75) Inventor: **Sun Jung Park**, Seoul (KR)

(73) Assignee: **LG Electronics Inc.**, Seoul (KR)

(**) Term: **14 Years**

(21) Appl. No.: **29/345,921**

(22) Filed: **Oct. 23, 2009**

(30) **Foreign Application Priority Data**

May 12, 2009 (KR) 30-2009-0020312

(57) **CLAIM**

I claim the ornamental design for an optical disk drive, as shown and described.

DESCRIPTION

FIG. 1 is a perspective view of an optical disk drive showing my new design:

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.
